UNITED STATES PATENT OFFICE.

SAMUEL H. GARRETT, OF PHILADELPHIA, PENNSYLVANIA, ASSIGNOR TO ENERGY ELEVATOR COMPANY, OF PHILADELPHIA, PENNSYLVANIA, A CORPORATION OF PENNSYLVANIA.

ACTUATING MECHANISM FOR THEATRICAL CURTAINS.

SPECIFICATION forming part of Letters Patent No. 766,238, dated August 2, 1904.

Application filed May 13, 1904. Serial No. 207,785. (No model.)

To all whom it may concern:

Be it known that I, SAMUEL H. GARRETT, a citizen of the United States, residing at the city of Philadelphia, in the county of Philadelphia and State of Pennsylvania, have invented certain new and useful Improvements 5 in Actuating Mechanism for Theatrical Curtains, of which the following is a specification.

My invention has relation to drop or safety 10 curtains for theaters or other places of amusement, and in such connection it relates more particularly to the raising and lowering mechanisms for such character of curtains operative from desired points of the stage, as well 15 as to means for controlling the same from different points of the stage.

The principal objects of my invention are, first, to provide a drop or safety curtain with 20 means for controlling the ascent and descent from various points or positions of the stage; second, to provide such a curtain with means whereby it may be raised or lowered before attaching the curtain to its counterweight 25 means to permit of repairs thereto or storage of the same, and, third, to provide a curtain of the character described with raising mechanism and with means for breaking the descent of the curtain under the influence of gravity to thereby bring the curtain in its descent 30 gradually to its lowered position.

My invention, stated in general terms, consists of actuating mechanism for theatrical or other curtains constructed and arranged in substantially the manner hereinafter described 35 and claimed.

The nature and characteristic features of my invention will be more fully understood from the following description, taken in connection with the accompanying drawings, 40 forming part hereof, in which—

Figure 1 is a view, partly in elevation and partly in section, of a drop or safety curtain and its actuating mechanisms, embodying main features of my present invention, looking at 45 the same from the back of the stage. Fig. 2 is an enlarged front elevational view of the main and auxiliary mechanisms for control-

ling the raising and lowering of the curtain. Fig. 3 is a side elevational view, partly in section, of the mechanism shown in Fig. 2, certain parts being removed for the sake of clearness. Fig. 4 is an enlarged detail view of one of the main operating-drums, from the cable of which drum the curtain is connected and provided with a safety device to control the 55 extent of unwinding of the cable from the drum. Fig. 5 is a front elevational view in detail of the friction device for controlling the band-brake of the auxiliary operating mechanism for the curtain. Fig. 6 is an enlarged sectional and elevational view in detail of a device to permit of the movement in one direction only of the main operating-sheave, and Fig. 7 is an enlarged detail view in section of a dash-pot arrangement for controlling the gradual stoppage of the curtain in its descent to its lowermost position. 60

Referring to the drawings, the curtain *a* is shown as suspended in its lowermost position to the rear of the opening *a'* (illustrated in 70 dotted outline in Fig. 1) of the proscenium-wall of a theater or other amusement edifice by means of suitable cables *a''*, adapted to be wound onto a series of drums *a'''*, suitably and securely keyed to the main lifting-shaft *b* of 75 the curtain elevating and lowering mechanisms of my invention. The cables *a''* are of sufficient length to reach from the drums *a'''* to the stage *a'* to facilitate attaching or detaching the curtain. In confined situations—80 that is, where the space is limited in which the curtain is located to be raised and lowered—in such instance the cables *a''* are attached to a batten *a⁴*, secured to the curtain at a point below the top thereof. That portion of the curtain between the batten *a⁵* and the batten *a⁶* at the top of the curtain is raised by means of cables *a⁷*, secured to the batten *a⁵* and traveling over wheels *a⁸*, loosely mounted on the shaft *b*. These cables are provided 85 at their free ends with weights *a⁹*. It will be understood that while the curtain is rising to its uppermost position that portion of the curtain between the battens *a⁵* and *a⁶* will fold

over and permit the other portion to rise. The lifting-shaft b also has keyed thereto a drum d , upon which is wound a cable d' , carrying at its end a suitable weight e for balancing the weight of the curtain. The cable d' is so arranged upon its drum d that when the curtain is raised by the rotation of the lifting-shaft b and the cables a^2 are wound on their respective drums a^3 the cable d' will be 10 unwound from its drum d , and vice versa. The cable d' is guided over suitable idler-pulleys d^2 to any convenient point at which it is desired to locate the weight e . This weight e is arranged within a box e' , and depending 15 from the bottom of said weight is a chain e^2 of sufficient weight to balance the weight of the cables a^2 as they are unwound from their drums a^3 in the descent of the curtain. It will 20 of course be understood that when the curtain is in its raised position the chain e^2 will lie in a heap at the bottom of the box e' . The lower end of the chain e^2 is secured to a piston-rod f' of a dash-pot f , securely fastened at the 25 bottom of the box e' . The dash-pot f (illustrated in detail in Fig. 7) comprises a cylinder f^2 , traversed by a piston f^3 and provided at its upper end with a valve f^4 of any suitable construction to control the egress of the air from the upper end of the cylinder. This 30 dash-pot is so arranged that the curtain will be brought to a gradual stop at its lowermost position without shock or jar.

The curtain-lifting mechanism comprises in addition to the lifting-drums a^3 a sheave-wheel g , mounted upon the lifting-shaft b and provided with an endless rope g' , adapted to be operated to raise the curtain from the fly-gallery h of the theater. This sheave-wheel g is permitted to turn in but one operative direction by means of the device i . (Illustrated in detail in Fig. 6.) This device has inclined faces i' , between which and the wheel g are placed rollers i^2 , adapted to jam against the sides of the rim of the sheave-wheel g when turned in one 45 direction, yet leaving the sheave-wheel free when turned in a contrary direction to raise the curtain. The sheave-wheel g is loosely mounted upon the shaft b and is adapted to be locked thereto by means of a friction-clutch k . 50 It will therefore be understood that when the sheave-wheel g is locked to the lifting-shaft b the curtain can only be raised, and when it is desired to lower the curtain it is necessary to disconnect the sheave-wheel g from the lifting-shaft b . To operate the friction-clutch, the lever k' is attached to an endless rope k^2 , which runs over suitable guide-pulleys k^3 and k^4 to such points from which it may be desired to lower the curtain from the stage and 55 fly-gallery. In Fig. 1 this controlling-rope k^2 is shown running to both the fly-gallery and to the stage, so that the curtain can be lowered from either point. The curtain a is slightly heavier than the balancing-weight e ,

so that when the sheave-wheel g is disconnected from the lifting-shaft b by means of the friction-clutch k the curtain will readily descend by gravity.

When it is desired to attach or detach the curtain for repairs or otherwise, it is necessary to lower the top of the curtain to the stage, and to accomplish this result the balancing-weights must be disconnected and the dead-weight of the curtain must be handled by the lifting mechanism. It would not be 75 possible to raise the curtain by means of the sheave-wheel g and rope g' without the assistance of the balancing-weight e . Therefore in order that the curtain may readily be handled when the balancing-weight is detached 80 there is provided the following auxiliary lifting mechanism: On the end of the lifting-shaft b is secured a gear-wheel m , which is adapted to mesh with a pinion m' , slidably arranged on a shaft m^2 . Ordinarily the pinion m' is not in engagement with the gear m , (see Fig. 2;) but when it is desired to use the auxiliary lifting mechanism the pinion m' is slid along the shaft m^2 until it meshes with the gear m . On the shaft m^2 is mounted a large 90 sheave-wheel m^3 , provided with an endless rope m^4 , adapted to be operated from the fly-gallery h . The rim of the sheave-wheel m^3 is provided with a band-brake m^5 . The mechanism for operating this band-brake comprises 95 a lever n , pivoted, as at n' , and carrying a weight n^2 , tending normally to release the band-brake from its engagement with the rim of the sheave-wheel m^3 . To the outer end of the lever n is secured a cord or rope o , adapted to raise the lever n to cause the band-brake to engage the rim of the sheave. The cord o is adapted to run over a series of friction-rollers o' and to a point in proximity to the fly-gallery h , from which it is adapted to be 100 operated. At the free end of the cord o is secured a weight o^2 , serving to a certain extent to balance the weight n^2 on the lever n and acting in conjunction with the weight n^2 and friction-rollers o' to lock the band-brake either 105 in or out of engagement with the rim of the sheave m^3 .

In Fig. 4 of the drawings there is illustrated one of the drums a^3 for raising the curtain. As hereinbefore described, the lifting-cables a^2 are of sufficient length to reach from the drums to the stage. Ordinarily, however, only about half of this length is used, and it is possible in case of an accident, such as the breaking of the cable carrying the balanceing-weights, that the entire curtain would drop to the stage. To prevent such a possibility, the safety device shown in Fig. 4 is employed, comprising a band r , clamped around the cable on the drum in such a position that only the required amount of cable will be permitted to unwind from the drum in the descent of the curtain.

Having thus described the nature and objects of my invention, what I claim as new, and desire to secure by Letters Patent, is—

1. A device of the character described, comprising a curtain, a series of cables from which the curtain is suspended, a series of drums upon which said cables are adapted to be wound to raise the curtain, a shaft upon which said drums are mounted, in combination with means for balancing the weight of the curtain, comprising a drum mounted upon said shaft and upon which is wound a cable carrying a weight at its free end, said cable being so arranged as to be unwound when the curtain-raising cables are wound on their respective drums.
2. A device of the character described, comprising a curtain, a series of cables from which said curtain is suspended, a series of drums upon which said cables are adapted to be wound to raise the curtain, in combination with means for balancing the weight of the curtain, and means for gradually bringing the curtain to a stop at its lowermost position.
3. A device of the character described, comprising a curtain, a series of cables from which said curtain is suspended, a series of drums upon which said cables are adapted to be wound to raise the curtain, in combination with means for balancing the weight of the curtain, and means for balancing the weight of the cables as the same are wound or unwound from their respective drums.
4. A device of the character described, comprising a curtain, a series of cables from which said curtain is suspended, a series of drums

upon which said cables are adapted to be wound to raise the curtain, a shaft upon which said drums are mounted, means for locking the shaft against rotation to prevent unwinding of the cables from their respective drums, means for unlocking the shaft to permit the curtain to descend and means for controlling the unlocking means from any desired point.

5. A device of the character described, comprising a curtain, a series of cables from which said curtain is suspended, a series of drums upon which said cables are adapted to be wound to raise the curtain and means for balancing the weight of the curtain, in combination with means for raising the curtain when the balancing means is detached.

6. A device of the character described, comprising a curtain, a series of cables from which said curtain is suspended, a series of drums upon which said cables are adapted to be wound to raise the curtain, a shaft upon which said drums are mounted, in combination with means for raising the curtain when the balancing means is detached, comprising a gear-wheel mounted upon the shaft carrying said drums, a pinion normally out of engagement with said gear-wheel, but adapted to be slid into engagement with the same and means adapted to rotate said pinion.

In testimony whereof I have hereunto set my signature in the presence of two subscribing witnesses.

SAMUEL H. GARRETT.
